DISPLAY STAND

Thornton E. Dartt, Cameron, N. Y.

Application May 3, 1949, Serial No. 2,417

Term of patent 14 years

(CL. D80—9)

To all whom it may concern:

Be it known that I, Thornton E. Dartt, a citizen of the United States of America, residing at Cameron, in the county of Steuben and State of New York, have invented a new, original, and ornamental Design for Display Stand, of which the following is a specification, reference being had to the accompanying drawings, forming a part thereof.

In the drawings:

Fig. 1 is a view in front elevation of a display stand, showing my new design;

Fig. 2 is a top plan view of the same; and

Fig. 3 is a side elevation.

I claim:

The ornamental design for a display stand, as shown.

THORNTON E. DARTT.
